US0D1053358S

(12) **United States Design Patent** (10) **Patent No.:** **US D1,053,358 S**
(45) **Date of Patent:** **** Dec. 3, 2024**

(54) **STETHOSCOPE HOLDER**

(71) Applicant: **Shenzhen Guerben Technology Co., Ltd.**, Shenzhen (CN)

(72) Inventor: **Donglin Jia**, Shenzhen (CN)

(73) Assignee: **Shenzhen Guerben Technology Co., Ltd.**, Shenzhen (CN)

(**) Term: **15 Years**

(21) Appl. No.: **29/843,649**

(22) Filed: **Jun. 22, 2022**

(51) LOC (14) Cl. **24-02**

(52) U.S. Cl.

USPC **D24/167**

(58) **Field of Classification Search**

USPC D24/167, 134; D3/203.1

CPC A61B 7/00

See application file for complete search history.

(57) **CLAIM**

The ornamental design for a stethoscope holder as shown and described.

DESCRIPTION

FIG. 1 is a front, right and top perspective view of a stethoscope holder, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines in the drawings depict environmental structure and boundaries and form no part of the claimed design.
